UNITED STATES PATENT OFFICE.

JOHN FOSTER, OF ROCHESTER, NEW YORK.

STANCHION.

No. 918,783.

Specification of Letters Patent.

Patented Feb. 27, 1906.

Application filed June 5, 1905. Serial No. 263,811.

To all whom it may concern:

Be it known that I, JOHN FOSTER, a citizen of the United States, residing at Rochester, in the county of Monroe and State of New York, have invented certain new and useful Improvements in Stanchions; and I do declare the following to be a full, clear, and exact description of the invention, such as will enable others skilled in the art to which it applies to make and use the same.

My invention relates to improvements in cattle-stanchions; and it consists in the novel construction, combination, and arrangement of devices herein shown and described.

One object of the invention is to provide a device of this character which is of simple construction, comparatively inexpensive of production, durable in use, and efficient in operation.

Another object of the invention is to provide a stanchion which is light and strong and comfortable for the animal confined therein.

The above and other objects, which will appear as the nature of the invention is better understood, are accomplished by the construction illustrated in the accompanying drawings, in which—

Figure 1 is a front view of a stanchion, showing it in its closed position in full lines and in its open position in dotted lines. Fig. 2 is a side elevation of the stanchion. Fig. 3 is a detail sectional view, on an enlarged scale, of the head of the stanchion, showing the locking-latch for the swinging side member or bar; and Fig. 4 is a detail sectional view taken on the line 4-4 in Fig. 3.

Referring to the drawings by numeral, 1 denotes my improved stanchion, which comprises two side members or bars 2, 3, a connecting bottom member or base 4, and a top member or head 5. The upright bars or members 2, 3 are preferably formed of hollow steel tubing, and the base 4 and head 5 are preferably in the form of castings. The side member or bar 3 is riveted or otherwise fastened in a tubular socket 9, formed at one end of the base 4, and at the opposite end of the latter is formed a slotted or recessed portion 10, in which is pivoted the lower end of the side member or bar 2. This pivotal connection is effected by riveting or otherwise fastening in the lower end of the tube 2 a plug having a tongue 11, which is adapted to project into the recess or bifurcated portion 10 of the base 4 and to receive the pivot bolt

or screw 12. The upper end of the said member or bar 3 is riveted or otherwise fastened in a tubular socket 13, formed at one end of the head 5. The upper free end of the swinging member or bar 2 is adapted to be fastened to the opposite end of the head 5 by a latch device 14, which comprises a hook-shaped member 15 upon the free end of the bar 2, a guide member 16, formed at one end of the head 5, and a swinging latch 17, pivoted upon said head. The member 15 is in the form of a curved hook formed upon a plug 18, which is riveted or otherwise fastened in the upper end of the tube 2. The guide member 16 of the latch device comprises a slot or recess 19, formed in one end of the head 5, and oppositely-disposed grooves 20, formed in the walls of the slot or recess 19 and adapted to receive lateral projections 21 upon the opposite sides of the inner portion of the hook 15, as clearly shown in Figs. 3 and 4 of the drawings. The slot 19 and grooves 20 guide the hook beneath the upwardly-curved outer end 22 of the latch 17, so that said end of the hook 80 will enter a slot or opening 23, formed in said end of the latch. The latch 17 is pivoted, as shown at 24, centrally in a longitudinal slot 6, formed in the head 5, and has a projecting finger-piece 25 at one of its ends to permit it 85 to be readily operated. The latch or latch-lever 17 has its slotted end held normally in engagement with the head 5 by a coil-spring 26, which has one of its ends secured to a lug upon said latch and its other end to a rivet or 90 pin 27, located in the slot 6 in said head 5.

The stanchion is adapted to be supported in a vertical position by suitable chains or other flexible connections 28, provided at its top and bottom, and the opening movement 95 of the swinging side member or bar 2 is adapted to be limited by a chain 29, which has one of its ends secured to the free end of the latter and its opposite end to the head 5 or to the upper chain 28. The use of the 100 chain 29 renders the device more convenient to handle and prevents injury to the hinge at the lower end of said swinging member.

The construction, operation, and advantages of the invention will be readily understood from the foregoing description, taken in connection with the accompanying drawings. It will be seen that by swinging the bar or member 2 from its dotted-line position (shown in Fig. 1) to its full position, after 110 the animal's head has been placed between the side bars, the curved upper end of the

hook 15 will elevate the latch 17 until the hook enters the slot 23 in said latch, whereupon the spring 26 will return the latch to lock the bar 2 in its closed position. By depressing the finger-piece 25 of the latch its slotted end may be readily disengaged from the hook 15, so that the member 2 may be swung outwardly to its opened position.

Various changes in the form, proportion, and the minor details of construction may be resorted to without departing from the principle or sacrificing any of the advantages of this invention.

What I claim is—

15. 1. A stanchion comprising a pair of bars, one of which is adapted to swing, a hook upon said swinging bar, lateral projections adjacent to said hook, a head upon the other of said bars and formed with a recess to receive said hook and with grooves to the walls of said recess to receive said projections and a swinging latch upon said head and formed with a slot to receive said hook, substantially as described.
25. 2. A stanchion comprising a tubular side member, a base secured to one end of said member, a slotted head secured to the other end of said member, a tubular swinging side member pivotally connected to one end of said base, an outwardly-extending hook 14 upon the free end of said side member, a guide upon one end of said head, a latch pivoted within said head and formed with a slot to receive said hook 14, a spring connected to said latch and head, said latch having a finger-piece 25, a flexible connection 29 attached to said swinging side member and to

said slotted head to limit the opening movement of said swinging member, and a chain for suspending said stanchion, substantially as described.

3. A stanchion comprising two tubular side members a cast base having a tubular socket at one end to receive one of said members and a slotted or bifurcated portion at its opposite end, a plug secured in one of said members and having a tongue adapted to be pivoted in the recess or bifurcated end of said base, a head having a socket member at one end adapted to receive the upper end of one of said side members and formed at its opposite end with a guide to receive the upper end of the other of said side members, said guide comprising a slot or recess formed with grooves in its walls, a hook upon the upper end of the pivoted side member adapted to enter the slot of said guide, lugs upon said hook to enter the grooves of said guide, a latch pivoted in a slot in said head and formed with an upturned slotted end adapted to engage said hook, a finger-piece upon said latch, a spring for holding said latch normally in engagement with said hook, and a chain or other flexible connection for limiting the swinging movement of said pivoted side member.

In testimony whereof I have hereunto set my hand in presence of two subscribing witnesses.

JOHN FOSTER
